LOCOMOTIVE SUPERHEATER
CONSTRUCTION

John A. McGrew, Albany, N. Y.

Application November 4, 1933, Serial No. 696,726

4 Claims. (Cl. 122—481)

This invention relates to superheater units for boilers and particularly to improvements in combination superheater and fire arch constructions for locomotive boilers of the type disclosed 5 in my prior Patent No. 1,918,655, issued July 18, 1933.

In the patent just referred to, a superheater is disclosed which is positioned in the firebox of a locomotive boiler, this superheater being so 10 formed and so disposed in the combustion space of the boiler that it comprises not only a means for effecting the superheating of the steam developed in the steam space of the boiler but also performs the functions of a fire arch or fire 15 bridge, deflecting the flame and products of combustion originating in the firebox grate rearwardly and upwardly in the customary manner so that such flame and gas do not pass directly to and into the fire tubes of the boiler. The 20 present invention contemplates an improved construction for this superheater unit whereby it is rendered more durable in use, without at the same time making it either more expensive to construct or heavier and without sacrificing any 25 of the advantages realized by the specific form of superheater unit first patented.

It will be appreciated by those skilled in the art that a superheater unit positioned in the firebox of a locomotive is subjected to intense heat 30 and that such a unit is also at times subjected to very considerable vibration due to motion of the locomotive. When the superheater unit is subjected to intense heat and considerable vibrations, there is a tendency for the metal of which 35 it is fabricated to yield and for the superheater to become distorted. It is undesirable to place in the firebox bracing or sustaining rods inasmuch as these add to the complexity of the structure and the weight of the locomotive. I have 40 therefore perfected a superheater unit in which, by the re-design and rearrangement of its own parts or elements, a stronger and more durable unit is realized.

Thus, in my prior patent the superheater unit 45 comprises essentially a plurality of straight parallel tube portions connected at their ends by bends, these parallel portions being positioned in an inclined plane in the inlet and outlet branches and being unsupported from their 50 lower sides. The improved superheater unit which comprises the subject matter of the present invention contemplates that these parallel portions of the unit be horizontally disposed, although still arranged in an inclined plane, and 55 that the inlet and outlet branches of the super-

heater lie beneath the same and in contact therewith, thus constituting supporting members for the main portion of the superheater and eliminating any tendency of portions of the unit to sag or become distorted in use. I contemplate 5 that the rearrangement of the various portions of the unit may be made in various ways to render the entire assembly self-supporting, and in the accompanying drawing I have illustrated one satisfactory construction by way of example. 10

In the drawing:

Figure 1 is a side view of the rear end of a locomotive boiler, partly in elevation and partly broken away to show the superheater unit and the interior construction of the boiler; 15

Figure 2 is a top plan view of the same, partly broken away to show details of the superheater unit and boiler construction;

Figure 3 is a section on line 3—3 of Figure 1; 20 and

Figure 4 is a section on line 4—4 of Figure 1.

The outer shell of the boiler is indicated at 10 and the combustion space at 11. The crown sheet is indicated at 12, tube sheet at 13, rear throat sheet at 14, and fire tubes at 15. The boiler grate 25 is not shown and may be of any well-known type such as now employed in connection with boilers of the construction illustrated. The superheater unit is generally indicated at S and comprises essentially an elongated tortuous steam conduit, into one end of which saturated steam from the boiler steam space is passed and from the other end of which superheated steam moves toward a front end throttle and engine cylinders, as fully set forth in my prior patent previously referred 30 to. The superheater steam conduit has a plurality of portions 20, each of which is horizontally disposed, all of these parallel portions being positioned in a plane inclined to the horizontal and which is normal to a vertical plane passing through the longitudinal axis of the boiler. The ends of the horizontal portions are connected by bends 21 so that steam entering the lowermost such portion passes successively through the several portions until it reaches the uppermost portion. 35

The lowermost conduit portion 20 is connected by a bend 22 to a rearwardly and upwardly extending portion 23 which turns forwardly around the uppermost conduit portion 20 and extends horizontally to a point adjacent the rear tube sheet 13 where it is connected, preferably by welding, to the rear end of a saturated steam conduit 23' which communicates with the steam space of the boiler. Portion 23 of the super- 45 50 55

heater unit is hereinafter designated the inlet branch since it is through this portion that the steam flows to the main part or mid-section of the superheater comprising conduit portions 20. 5 The uppermost conduit portion 20 is connected by a downtake 24 to the lower end of the upwardly and rearwardly inclined section 25 of the superheater which section also has a horizontal portion extending forwardly in a horizontal direction toward the tube sheet 13, the end of this forwardly 10 extending portion being welded at 26 to the rear end of a forwardly extending offtake pipe 27 for superheated steam.

As set forth in my prior patent, steam conduits 23' and 27 are attached at their forward ends to the boiler structure and hence constitute supporting means for the superheater unit within the firebox, while at the same time permitting slight movements of this unit due to changes in dimension of the metallic parts of the boiler resulting from changes in temperature. The weight of 15 the superheater unit is carried by a cross rail 28, the ends of which are secured to the mud ring 29 of the boiler structure. Interposed between the rail 28 and the superheater are rest plates 30 upon which the superheater directly bears and with respect to which it may have slight rolling movements due to expansion and contraction of pipes 23' relatively to the remainder of the boiler structure. 20

Rows of firebrick are indicated at 30 and extend between the side walls of the combustion space to the superheater unit, and it will be appreciated that, in order that the products of combustion arising from the grate be deflected by the superheater unit after the manner of a fire-bridge, additional fire-bricks may be positioned, or refractory material of any type positioned at various points as desired, to prevent direct passage of the products of combustion into the fire tubes of the boiler. In cross-section the superheater conduit is preferably as shown in Figure 4, webs being provided for the purpose of rapidly transmitting the heat from the lower side of each 35 tube section to the upper side, thus preventing burning out of the lower side. These inwardly projecting webs likewise insure that all portions of the steam column passing rapidly through the superheater will be subjected to the necessary 40 heat to achieve the degree of superheat desired.

The parallel inlet and outlet branches 23 and 25 are in contact with the superposed horizontal portions 20 of the tortuous conduit and constitute supports for the entire mid-portion of the superheater. By thus forming the combination superheater and fire-bridge, it is rendered more stable 45 against the combined action of grate heat and vibration and without necessitating the use of reinforcing or bracing members of any kind and 50 without increasing the weight of the superheater structure itself.

It will be apparent that, in adapting the superheater to various types of locomotives, it may

be deemed desirable to make changes in the arrangement of the various sections of the tortuous conduit so that the unit possesses greater strength for a given weight of metal, and the invention contemplates that numerous such changes may be made without departing therefrom. 5

Having thus described the invention, what is claimed as new and desired to be secured by Letters Patent is:

1. In combination with a locomotive boiler having a firebox, of a combined superheater and fire bridge, said combined superheater and fire bridge comprising a single elongated conduit, an intermediate part of which comprises a series of straight portions arranged in substantial parallelism and close relationship in the plane inclined to the horizontal so as to rearwardly deflect flame and products of combustion, and the end parts of which are disposed substantially at right angles to the straight portions of said intermediate part and in spaced parallel relationship in a plane parallel to the plane of the intermediate part, said end parts underlying and supporting said intermediate part and being in turn supported by the boiler. 20

2. In combination with a locomotive boiler having a firebox, of a combined superheater and fire bridge, said combined superheater and fire bridge comprising an elongated conduit for steam having a plurality of portions arranged in substantial parallelism and generally in a common inclined plane, and spaced additional portions disposed in a parallel plane, said last mentioned portions being disposed transversely of said first mentioned portions and being adapted to underlie and support said first mentioned portions, said additional portions being in turn supported by the boiler. 30

3. In combination with a locomotive boiler having a firebox, of a combined superheater and fire bridge, said combined superheater and fire bridge comprising an elongated conduit for steam having an inclined tortuous intermediate portion and inlet and outlet branches, said inlet and outlet branches being disposed to underlie and support the intermediate portion and being in turn supported upon the boiler. 40

4. In combination with a locomotive boiler having a firebox, of a combined superheater and fire bridge, said combined superheater and fire bridge comprising an elongated conduit for steam having an inclined tortuous intermediate portion and inlet and outlet branches, said inlet and outlet branches being disposed to underlie and support the intermediate portion, the lowermost part of each branch having a bearing surface, and a supporting member extending transversely of the firebox upon which said bearing surfaces rest, the ends of said member being secured to the mud ring of the boiler. 50
